VENEER STRIP, COILS THEREOF, AND
METHOD OF PREPARING SAMEPaul R. Goldman, Andover, Mass., assignor to
Plymold Corporation, Lawrence, Mass., a corporation

Application October 21, 1942, Serial No. 462,800

4 Claims. (Cl. 144—309)

My present invention relates to the preparation of thin wood striping, wood veneer or plywood in strips of various widths and of indeterminate length made available in the form of coils or rolls for use in the manufacture of various structures and articles including particularly spirally wound pipe, tubes, conduits, structural members of general utility, and other cylindrical or tubular formations. More particularly the invention aims to provide a novel package, coil or roll of continuous thin wood strip substantially uniformly dimensioned throughout, together with an improved process and means for producing the same.

In the drawing illustrating by way of example one form of the article and of means for carrying out the manufacturing process:

Fig. 1 shows in elevation and somewhat diagrammatically a package of coiled veneer striping;

Figs. 2 and 3 respectively represent in plan and in side elevation a section of the wood material, including a region of union of two initially discontinuous lengths of the striping;

Fig. 4 is an enlarged longitudinal section at a strip joint; and

Fig. 5 is a largely diagrammatic view in side elevation representing apparatus appropriate for the practice of the manufacturing process of the invention.

The plywood or veneer strip material of the present invention may be utilized in various ways but is particularly adapted for use in forming spirally wrapped pipe, tubing, conduit and the like. In the formation of such tubular and other cylindrical structures the length of the veneer strip, to be continuous from end to end of the structure and unless laid parallel to the structure axis, must be greater than that of the structure, the more so where the strip is applied in a lengthwise progressive close spiral. The required strip length frequently therefore is greater than that ordinarily available in a single natural piece of thin wood material, whether cut spirally from the log or stock or otherwise.

Accordingly the invention provides for preparing a supply of thin wood or veneer striping of indeterminate extensive length, adequate to run continuously in a spiral from end to end of the given cylindrical or tubular structure. At the same time the invention also makes possible the utilization of relatively small or short logs and timber stock for forming the veneer striping, including what otherwise would be waste material for veneer-forming purposes. Also under the invention odd lengths of veneer, including left-over and even scrap pieces may be used in preparing the coils of tape-like veneer or thin wood strip.

Referring to the drawing in more detail, Fig.

1 represents a typical coil or roll of veneer strip in accordance with the invention, as seen in its package form ready for shipment or use. The illustration is not to scale, and is diagrammatic as to thickness of the wood strip and as to the diameter of the coil, both of which may vary within wide limits. In this packaged form, the coil, indicated as a whole by the numeral 5, comprises a continuous length of the veneer strip designated generally at 6.

The continuous strip of the coil is composed of a number of relatively short lengths of the thin flexible wood united endwise. This material usually is of the hard wood class, including such woods as birch, maple, mahogany, poplar, walnut and others, but for some purposes softer woods as for example some of the firs and even some varieties from the general class of soft woods may be used. The thin sheets and strips of the wood may be cut from the log or stock in any preferred manner including slicing or knife-cutting, as well as rotary cutting.

As to width, this thin flexible wood material for forming the coiled package may vary within a considerable range, according to the size of the tubing or other article to be manufactured, the coiled striping being supplied in the various widths as appropriate to the particular manufacture. Thus the strip width may range from a relatively narrow tape of about $\frac{1}{2}$ inch or even less, for the smaller articles, up to widths of 4 to 10 inches or more for the larger diametered manufactures. Likewise the gauge or thickness of the wood strip may range from an extreme thinness of about $\frac{1}{40}$ to $\frac{1}{100}$ of an inch up to the heavier veneers of $\frac{1}{2}$ inch and more, again largely depending on the particular article of ultimate manufacture. Generally the strip or tape as presented in the coiled package consists of a single ply or thickness of the wood, but in some cases it may comprise two or more wood plies superposed and suitably bonded together prior to coiling. In such plural ply forms the end unions of individual plies, to be described, 45 may coincide in the different plies or may be differently spaced along the strip as a whole.

As above indicated the flexible wood strip 6 of any particular coil or package 5 is continuous. In a given coil the total strip length may run 50 into hundreds or even a thousand feet or more, there being no definite limit in this respect other than that of the weight and diameter desired for any given coiled package, and the capacity of any apparatus for preparing and handling it. 55 Further, it is important that this wood strip or tape, especially with reference to its use for winding into tubing and cylindrical structures, shall be of substantially uniform thickness throughout. To provide such uniformity in a continuous strip formed of a considerable number of rela-

tively short pieces, yet with adequate strength at the joints, is a main object of the present invention. In the better grades of hard woods component pieces for the strip may be had in lengths of 40 to 50 feet or more. But if substantially shorter pieces of the thin strip or veneer can be utilized, despite the greater number of end joints involved, much wood stock and veneer not heretofore practically available for the purpose may be employed. This includes not only such medium lengths as 6 to 10 feet and thereabouts but also much shorter sections, sometimes not more than a foot or so long. Under the invention, by reason of the uniform and otherwise improved end jointing of the numerous component pieces, and whereby a relatively large number of frequently occurring joints is no objection, a wider range of wood material can be made use of, including what for present purposes generally heretofore has been regarded as waste or scrap.

Referring more particularly to Figs. 2 and 3, the portion of strip 6 as there shown comprises the trailing end of one initially separate piece 7 and the leading end of a next piece 8. These pieces 7 and 8, representative of any two lengths to be joined, whether the same or different wood stock, have been slit or trimmed to uniform width and preferably are of substantially the same gauge or thickness. In connecting the adjoining ends of any two strip pieces such as 7 and 8 the latter are substantially overlapped at a joint or union area as at 9, a bonding agent being supplied at the contiguous faces of the overlapped portions.

Desirably the transverse edges of the pieces to be joined are cut or trimmed on a bias, disposing them nonperpendicularly to the side edges of the strip, as at 7a, 8a, Fig. 2. The terminal edge of each piece is thus extended lengthwise of the strip, thereby reducing the chances of having transverse imperfections in the wood material presented along any considerable part of the terminal edge. Also, in the subsequent use of the strip, such diagonal terminal edge is caused to align generally with the axis of the tubular structure to which the strip is applied by spiral winding, so subjecting the material to less tensioning and internal stress along such terminal line of a component piece of the strip.

The union as a whole, such as at 9, may be further improved and tendency of cracking or fraying thereat reduced by spacing one end of the diagonal terminal line of a given piece 7 or 8 inwardly from the side edge with which such line, if extended, would define an internal acute angle. From such inset point, as indicated at 7b, 8b for example the terminal line extends perpendicularly, or more nearly so, to the adjacent side edge, as at 7c, 8c. Thus any acute projection at the end of a piece is avoided, while retaining the advantages of the diagonal terminus.

In addition to the foregoing, in the preparation of the strip to be coiled, the several successive pieces desirably are so selected and so slit or trimmed to width that the wood graining will be parallel or substantially so in the succeeding lengths, as indicated for example at 7d and 8d in Fig. 2. The several pieces generally are cut or arranged so that this graining, by which is meant any of the usual granular markings, lineal cellular formations or linings inherent in the thin wood material, extends predominantly in the direction lengthwise of each piece, as for example in Fig. 2. Such arrangement is well suited to a

majority of subsequent tubular applications of the strip, contributing both to radial or crush-resisting strength and to axial strength or rigidity. In some instances, however, the predominant grain direction may be at right angles to the longitudinal extent of the various component strip pieces or substantially so, or it may follow some intermediate angle. But in any case it is desirable that the granular formation at the overlapping end portions of successive pieces to be joined shall have an approximate mutual parallelism, thereby facilitating the bonding and to some extent an actual inter-penetration of the body substance of the overlapped pieces; see Fig. 4.

In Fig. 5 I have illustrated, largely diagrammatically, one form of apparatus suitable for practicing the method involved. The comparatively short portion of a wood strip 6 there shown includes a zone 9 of juncture of two successive pieces such as 7 and 8. These strip pieces have been prepared, cut and trimmed in the manner such as described in connection with Figs. 2 and 3, and their end joint areas, with the adhesive or other bonding agent applied, have been placed in mutually overlapping relation. Such agent may be any of various known plastic glues, cements and the like, including those of the urea formaldehyde type and those of the Tego type as used in aircraft construction, such agent being adapted for setting under pressure, whether with or without the application of heat. The strip pieces thus preliminarily connected are then subjected to substantial pressure, particularly at the region of juncture. Such pressure may be variously applied, in some cases before the pieces are connected and as a step preparatory thereto, but is conveniently accomplished at a compressing station from which the strip is advanced to a coiling means.

In Fig. 5 for example I have shown upper and lower rolls 11, 12 rotatively supported in opposed relation on a frame 13. The upper roll 11 is journaled in a bearing block 14 vertically slidable in a guide 15 on an arm 16, the latter pivoted as at 17 on the frame 13. Thus the arm 16 and upper roll 11 as a whole are subject to vertical adjustment, and the roll 11 is independently movable for loading and pressure adjusting purposes. This roll 11, desirably of a heavy construction, is urged into pressing engagement with the wood strip 6 passing below it, as by strong springs 18 held under compression in the bearing guides 15 at the respective ends of the roll. The pressure of these springs may be regulated as by means of threaded plungers 19 adapted to be turned down against them as by hand wheels 20.

At its end remote from its pivotal support the arm 16 is provided with a finely adjustable positive stop means illustrated as a stud 21 extending down through and having threaded engagement with the arm 16. The lower end of this stud extends through a fixed abutment 22 on the frame and has collars 23 fixed on it, one above and one below the abutment. In this manner the degree of approach for the pressure rolls 11 and 12 may be positively set to limit the same in accordance with the gauge or thickness desired for the particular strip 6. This setting of the rolls may be facilitated as by means of a stationary scale 24 graduated in small fractions of an inch or calibrated in terms of pressure, with a cooperating index 25 on the adjustable roll-carrying arm 16.

As already pointed out, the resultant continuous strip 6 is of uniform thickness, without ob-

jectionable thickening at the joined zones or areas such as 9. If for example the component pieces such as 7 and 8 are $\frac{1}{64}$ in. thick, the several joint areas 9 likewise are but little if any over $\frac{1}{64}$ in. thick instead of twice that thickness or more.

For a strip of $\frac{1}{64}$ in. thickness, merely as an example, the limiting stop 22, Fig. 5, is set to space the rolls 11, 12, by exactly $\frac{1}{64}$ in. or in some cases slightly less, for example $\frac{1}{80}$ in., when it is desired to exert some ironing or compressive action on the portions of the strip 6 between joints 9 in addition to the heavy compressive action at the latter. These joints or juncture zones 9, comprising overlapped end portions of two separate pieces ordinarily would be at least twice as thick as the non-lapped body portion of either piece such as 7 or 8. But as the connected pieces are advanced between the rolls 11, 12 any such excess thickness is compressively reduced. The weight of the overlying roll 11 and the strength of the springs 19 together with their pressure control means 20 are so calculated and arranged as to apply a compressive force at the joints 9 adequate to reduce them to the $\frac{1}{64}$ in. thickness selected in the illustrative example, rendering them substantially uniform with the remainder of the strip. The pressure thus applied is regulated to be such that the wood substance of the previously separate pieces at the overlapped areas is to a considerable extent inter-penetrated and compressed into a unitary mass, as facilitated by the parallel arrangement of the graining, the bonding agent at the same time being largely impregnated into the body of the pieces; see Fig. 4.

As above indicated, more or less pressure may be applied over the whole length of the strip, with some corresponding compressive and unifying effect also on the portions between joints. By controlling the pressure, as by the described positive regulated setting of the roll spacing and the independent adjustment of the top roll, the compressive action at the joint areas is made sufficient to provide for a substantial uniformity of thickness throughout the entire resulting strip, taking into consideration any thinning of its non-lapped portions between joints. If desired the strip may be passed successively through one or more additional pressure-applying stations such as that represented at the right in Fig. 5, or the ends of pieces to be overlapped may be compressively reduced preparatory to interconnecting them.

The connected strip 6 is advanced to a suitable winding core, reel or other coiling means, not shown but indicated by the arrow at the left in Fig. 5, for winding the strip into the coil package form such as that of Fig. 1. Prior to coiling the strip may be subjected to a burnishing, polishing or abrading action, such for example as by passage through sanding or other abrasive wheels 26, 27. These are shown as driven differentially or oppositely to the direction of travel of the strip, to apply a rubbing, burnishing or like action upon one or both faces of the latter. In this manner any rough or irregular areas, whether at the joints or elsewhere are smoothed, reduced or removed. It will be understood that travel of the strip to the coiler, and at other stages of the disclosed continuous process, is effected by feeding or advancing means, as for example pairs of opposed feed rolls as at 28, 29.

My invention, as to method, apparatus, and

product, is not limited to the particular steps, means and structure as herein illustrated or described by way of example, its scope being pointed out in my claims as follows.

5 I claim:

1. The method of preparing thin flexible wood strips for subsequent manufacturing purposes which comprises forming and assembling a plurality of elongated wood pieces of the width and thickness desired for the strip in a manner to present the graining predominantly in mutual parallelism, applying a bonding agent at end areas of pieces to be connected end to end, lapping said areas, subjecting the lapped areas to substantial pressure adequate to compress them to a thinness uniform with that of the individual component pieces, repeating said steps with successive pieces as facilitated by said mutually parallel graining arrangement to provide a continuous strip of indeterminate length, and freely coiling the strip into roll package form for subsequent off-feeding rotatively in any desired length thereof.

2. A thin flexible wood strip for manufacturing purposes, said strip having an indeterminate continuous length and being of substantially uniform thickness of the order of about $\frac{1}{100}$ to $\frac{1}{64}$ in., said strip comprising a plurality of component pieces of like thickness disposed in longitudinal series and with their graining in approximate mutual parallelism, such pieces having end areas compressively reduced to approximately but one-half the initial thickness of the given piece, said areas of trailing and leading ends of successive pieces being overlapped and bonded together to provide 30 an integrated joint of a thickness not substantially exceeding that of the component strips and the transverse edges of the jointed ends of the successive pieces being for a substantial portion of their extents non-perpendicular to their 35 longitudinal side edges.

3. A thin flexible wood strip according to claim 2 wherein the transverse edges of the jointed ends of the successive pieces are diagonally disposed over a portion of their extent, and along their 40 remaining extent are more nearly perpendicular to the longitudinal side edges of the strip.

4. As a new product of commercial manufacture, a supply roll package of wood veneer for 45 shipment, storage and use by feeding off therefrom rotatively in the manufacture of laminar veneer articles and the like, said package comprising a continuous strip of thin flexible wood veneer of indeterminate length and of substantially uniform thickness, said strip composed of 50 a plurality of individual relatively shorter thin flexible single-ply wood veneer pieces of like thickness and of uniform width throughout and having their predominant direction of graining in approximate mutual parallelism, adjacent end 55 portions of successive pieces being overlapped and bonded together flatwise and interpenetratively compressed into a substantially homogeneous connective portion generally uniform in thickness with the main body of the strip as facilitated by 60 said mutually parallel graining arrangement, the plurality of pieces so connected end to end being freely coiled convolutedly into the roll package of a desired diameter and having all coil turns 65 of the resultant strip free of adjacent turns, for subsequent off-feeding therefrom of a continuous veneer strip of indefinite length representing a 70 substantial multiple of any initial individual veneer piece.

PAUL R. GOLDMAN.

CERTIFICATE OF CORRECTION.

Patent No. 2,388,479.

November 6, 1945.

PAUL R. GOLDMAN.

It is hereby certified that error appears in the printed specification of the above numbered patent requiring correction as follows: Page 3, second column, lines 18 and 19, claim #, strike out the words "as facilitated by said mutually parallel graining arrangement" and insert the same after "pieces" first occurrence, line 17; and that the said Letters Patent should be read with this correction therein that the same may conform to the record of the case in the Patent Office.

Signed and sealed this 29th day of January, A. D. 1946.
